UNITED STATES PATENT OFFICE.

JOSEPH POPPER, OF BROOKLYN, NEW YORK, ASSIGNOR, BY DIRECT AND MESNE ASSIGNMENTS, OF ONE-HALF TO BAIRD-DANIELS CO., INC., OF NEW YORK, N. Y., A CORPORATION OF NEW YORK, AND ONE-HALF TO MRS. RUBY H. POPPER, OF BROOKLYN, NEW YORK.

AMUSEMENT DEVICE.

1,377,221.

Specification of Letters Patent. Patented May 10, 1921.

Application filed March 9, 1920. Serial No. 364,402.

To all whom it may concern:

Be it known that I, JOSEPH POPPER, a citizen of the United States, and a resident of the city of New York, borough of Brooklyn, in the county of Kings and State of New York, have invented a new and Improved Amusement Device, of which the following is a full, clear, and exact description.

This invention relates to an improved amusement device wherein the parts are so arranged that when made small they may act as a toy and give different pleasing effects, while the same parts may be utilized in advertising, whether large or small.

Another object of the invention is to provide a reflecting device associated with a movable light in such a manner that the moving of the light will cause the reflection to change in proportion to the movement of the light toward and from the reflector.

A still further object of the invention is to provide a device using one or more reflectors and a movable light positioned to move toward and from the center of the reflectors so as to co-act with the various reflectors at different times and to project a pleasing and more or less startling effect.

In the accompanying drawing:

Figure 1 is a front view of an embodiment of the invention shown arranged as an amusement device or toy.

Fig. 2 is a rear view of the upper part of the structure shown in Fig. 1.

Fig. 3 is a longitudinal vertical section 35 through Fig. 1 on line 3—3.

Fig. 4 is a fragmentary view on a reduced scale similar to Fig. 3, showing a modified form of movable light.

Referring to the accompanying drawing 40 by numerals, 1 indicates a support or standard to be grasped by the hand, said standard having an aperture 2 for receiving the revolving shaft 3, which shaft also extends through an aperture 4 in a bracket 5

45 riveted or otherwise connected to the standard 1. A pinion 6 is rigidly secured to the hollow shaft 3 and continually meshes with the comparatively large gear wheel 7, which is rotatably mounted on a suitable journal 50 8 carried by the standard 1. Rigidly secured to the shaft 3 are reflectors 9 and 10, said reflectors being spaced by a suitable spacing member 11. Reflector 9 is pro-

vided with reflecting surfaces 12, 13 and 14 arranged at different angles and also provided with different colors whereby when light is projected against the different colors a proper colored reflection will be provided. The reflector 10 is also provided with reflecting surfaces 15 and 16 of different colors, the arrangement in the drawing being an orange or gold color on the surface 15. Where the device is to be used for advertising purposes the surface 14, or in fact any of the reflecting surfaces may be provided with names, printed or otherwise provided thereon. It is understood that all of the reflectors could be merely bright reflectors, or could be colored in any desired manner for producing different effects.

As shown in Fig. 3 a source of light 17 is provided with the use of what is commonly known as a sparkler 18 which sparkler has a combustible matter mounted on the metal rod 19, said light fitting into the hollow shaft 3 by which it is held in place. The combustible matter of the sparkler 18 may be extended any desired distance outwardly, and may be of one or many colors. When the outer end is lit the various reflectors will begin to operate and reflect the light, most of the light being reflected from the surfaces 12, 13, and 14. As the light 17 travels inwardly or toward the reflectors the outer reflectors 12, 13 and 14 will gradually be cut out successively and the reflecting surfaces 15 and 16 act in a more pronounced manner. If the reflectors are rotated by actuating the wheel 7 during the movement of the light 17 the various reflecting surfaces 80 will present rings of reflected light, which rings gradually get smaller and smaller as the light travels toward the reflectors. In fact the reflection becomes such a small ring as it approaches the reflecting surface 15 as 85 to have almost the appearance of a ball of fire.

When used as a toy the arrangement as shown in Fig. 3 wherein the sparkler is used, is desirable. When the device is used 100 for advertising purposes the same arrangement could be used, or the modified arrangement as shown in Fig. 4, wherein the shaft 3' is preferably greater in diameter than shaft 3 and carries a tubular member 105 20 through which the electric supply wires

21 extend to the bulb 22. By providing this arrangement an electric lamp could be used and could be moved inwardly and outwardly as desired while the reflectors are 5 rotated or while they are standing still.

What I claim is:

1. A device of the character described comprising a reflector having a plurality of reflecting surfaces at different angles, and 10 a light movable along the axis of said reflector.

2. A device of the character described comprising a reflector having a plurality of reflecting surfaces arranged at different angles, means for supporting said reflector, and a light producing member carried by 15 the reflector support, said light producing member being such that the light will travel toward said reflector.

20 3. In a device of the character described a reflector, a hollow shaft for supporting said reflector, said reflector having a plurality of colored reflecting surfaces arranged at different angles, and a sparkler having the 25 stem mounted in said shaft, and means for rotating said shaft.

4. A device of the character described comprising a reflector having a plurality of annular reflecting surfaces arranged at different angles, a second reflector having a 30 plurality of annular reflecting surfaces at different angles, said second reflector being smaller than the first mentioned reflector, a shaft for supporting both of said reflectors, 35 and means for connecting a light with said shaft so that the light will project on to all of said reflecting surfaces.

5. A device of the character described comprising a pair of reflectors, one reflector 40 being smaller than the other and arranged so that the small reflector will be centrally of the large reflector and spaced a short distance therefrom, both of said reflectors having a plurality of independent reflecting 45 surfaces, means for moving a light toward said surfaces, and a standard for supporting said reflectors.

6. A device of the character described comprising a pair of super-imposed reflec-

tors, one reflector being larger than the 50 other, a hollow shaft for supporting said reflectors, and a light carrying member 55 slidingly mounted in said shaft and capable of movement toward and from the center of said reflectors.

7. In a device of the character described, a support, a pair of super-imposed reflectors, a shaft carried by said support for supporting said reflectors, one of said reflectors being smaller than the other, and 60 each reflector being provided with a plurality of different reflecting surfaces at different angles, each of said surfaces being colored, and light means carried by said shaft, said light means being capable of 65 causing the light to travel toward said reflectors.

8. A device of the character described comprising a pair of reflectors one being larger than the other, said reflectors being 70 spaced apart but super-imposed, a hollow shaft extending through said reflectors centrally thereof and a light movable toward the center of said reflectors supported by 75 said shaft, and a support for supporting said shaft and reflectors.

9. A device of the character described comprising an outer reflector formed with a plurality of different reflecting surfaces arranged at angles to each other, an inner reflecting surface provided with a plurality of colored reflecting surfaces positioned to 80 cut off the outer reflecting surface from the light when the light is moved a predetermined distance toward the center of the inner reflector, and means for supporting a 85 light in front of said reflectors capable of causing the light to move toward the center of the small reflector.

10. An amusement device of the character 90 described comprising a reflector, and a light movable along the axis of said reflector.

11. An amusement device of the character described comprising a concave reflector, and a light movable along the axis of said 95 reflector in front of the concave face of the reflector.

JOSEPH POPPER.
